[57] CLAIM

The ornamental design for a telephone handset, as shown and described.

DESCRIPTION

FIG. 1 is a front, receiver-end and side perspective view of a telephone handset showing our new design;

FIG. 2 is a back plan view thereof;

FIG. 3 is a side elevational view of the telephone handset, the opposite side being a mirror-image thereof; and,

FIG. 4 is an end elevational view of the telephone handset, the opposite end being identical therewith.

Fig. 1

*Fig. 2**Fig. 3**Fig. 4*
